UNITED STATES PATENT OFFICE.

JOHN F. CALAHAN, OF LOS ANGELES, CALIFORNIA, ASSIGNOR OF ONE-HALF TO
HERBERT B. PERDEW, OF LOS ANGELES, CALIFORNIA.

STAY-MACHINE.

1,272,773.

Specification of Letters Patent. Patented July 16, 1918.

Application filed January 30, 1917. Serial No. 145,542.

To all whom it may concern:

Be it known that I, JOHN F. CALAHAN, a citizen of the United States, residing at Los Angeles, in the county of Los Angeles and 5 State of California, have invented a new and useful Improvement in Stay-Machines, of which the following is a specification.

My invention relates to a machine for making stays designed to be used on wire fences. It very frequently happens that the strands of which wire fences are constructed sag in places and when such a condition occurs it requires considerable labor to straighten the wires. This labor has been 10 reduced to a minimum by the use of a very simple expedient such as a stay designed to be placed upon the fence and engage the respective strands of the wire spacing the same apart and supporting the same. 15 One of the principal objects of my invention is to produce a machine of simple form and construction upon which may be cheaply made fence stays of simple form which may be used for the purpose of spacing and supporting the strands of such fences. 20

Other objects and advantages will appear hereinafter in the following specification:—

Figure 1 is a side elevation of a fence showing the type of stay made upon the 30 machine as used.

Fig. 2 is a plan view of the machine embodying my invention.

Fig. 3 is a longitudinal side view partly in section of the machine shown in Fig. 2;

35 Fig. 4 is a vertical cross-sectional view on line 4—4, Fig. 3; and

Fig. 5 is an enlarged plan view partly in section of the forming mechanism of the machine.

40 The fence stay made upon the machine is illustrated in Fig. 1, as shown at 7, and consists of a straight wire 8 turned back upon itself at 9 and such turned back portion loosely coiled upon the straight wire 8 as indicated at 10. Such portion 10 is of considerable larger diameter than the wire 8 thereby leaving a series of spaces between the coil and the straight wire. The stays are used by twisting the stay over the upper 45 strand 11 of the fence then holding the strand 12 the proper distance from the strand 11 and the stay twisted into engagement therewith after which the strands 13 and 14 in succession are properly spaced and 50 the coil 10 twisted into engagement there-

with, the coil 10 holding the strands of the fence the proper distance apart and thereby preventing relative movement of the strands.

The machine consists of a base 15 upon which is secured by means of suitable bolts 16, a head-stock 17, and opposite thereto at the other end of the machine is secured by means of suitable bolts 18, a tail-stock 19. The head-stock 17 and the tail-stock 19 are longitudinally connected by means of longitudinally disposed guide rods 20. Slidably mounted on the guide rods 20 is a forming die 21 consisting of a body portion 22 having a lug 23 extending upwardly therefrom at one side of the same and a wall 24 extending upwardly at the inner end of the die, said wall 24 terminating in a beveled edge 25 spaced apart from the adjacent edge of the lug 23 to form a throat 26 or entrance opening for the wire to be fed to the die. 60

28 designates a longitudinally disposed shaft mounted in the head-stock 17, to the inner end of which is secured by means of a pin 29 a hollow cylindrical mandrel 30, the outer end of which extends through a 65 hole 31 in the wall 24 of the forming die. The outer end of the mandrel 30 is notched as indicated at 32. 70

Slidably mounted upon the guide rods 20 is a follower 34 having a lug 35 with an 80 opening 36 therein in alignment with the hole 31 in the forming die, the opening 36 terminating in its upper portion in a transverse slot 37 which extends through the lug. 85

38 designates coiled springs upon the 90 guide rods 20 interposed between the follower 34 and an upright 39 formed on the tail-stock 19. The forming die 21 is elastically held in the position shown in Figs. 2 and 3 by the following mechanism: 95

40 designates an eye secured to the under side of the forming die to which eye is secured a cable 41. The cable passes over a sheave 42 mounted upon a pin 43 in the tail-stock 19, then passes around a sheave 44 in 100 a block 45, thence around a sheave 46 mounted on a bracket 47 on the base of the machine and having its end secured in an eye 48 in the block 45. The other end of the block is secured to a coiled spring 49 which 105 in turn is secured to an eye 50 mounted upon the base 15 of the machine, the forming die by this apparatus being elastically held against the follower 34 which in turn is cushioned upon the springs 38 against the 110

upright 39 of the tail stock 19. The follower 34 is particularly for the purpose of affording a support for the end of the mandrel 30 as the operation advances, the forward movement of the follower 34 being limited by a headed bolt 51. The headed bolt 51 is slidably mounted in the upright 39 to limit the forward movement of the follower. A coiled spring 53 is provided on the bolt 51 for elastically pushing the follower forward as the forming die is moved ahead during the forming operation. The forming die is moved in the direction of the arrow shown in Fig. 2 by means of the following mechanism:

Secured to an ear 55 formed on the die 21, by means of a suitable bolt 56 is a link chain 57 which at one end passes around a pulley 58 mounted on the tail-stock 19 and at the other end extending around a sprocket 59 formed on a clutch member 60 loosely mounted upon a stub shaft 61 but fixed thereto rotatively and designed to be placed in engagement with the member 62, and thereby drive the sprocket 59, by means of a wedge arm 64 formed as one leg of a bell-crank 65 pivotally mounted at 66 upon a bridge 67 formed on the head-stock 17. The movement of the bell-crank 65 is controlled by means of a rod 68 slidably mounted on brackets 69 on the base of the machine, such rod having a handle 70 secured at one end thereof.

71 designates a stop which may be mounted at any desired point upon the rod 68 for the purpose of automatically stopping the machine as hereinafter described. The clutch member 62 and shaft 61 are driven by means of a beveled gear 73 from a spur 74 mounted on the shaft 28, which shaft 28 in turn is driven by a gear 75 mounted thereon, which gear 75 is driven by a gear 76 mounted upon the shaft 77 of an electric motor 78 mounted upon an extension 79 of the base of the machine.

The machine is operated in the following manner:

A piece of wire 8 approximately twice the length of the stay to be made is used, one end of the wire being inserted in the mandrel 30 until the end of the wire strikes against a filling block 81, there having been a filling block or blocks inserted until the distance between the last filling block and the open end of the mandrel is approximately the same as the length of the stay to be made on the machine. The wire is then bent at right angles as shown in Fig. 2 so that the bent over portion 9 of the wire lies in the notch in the outer end of the mandrel. The machine is then set in motion by shifting the rod 68 which moves the bell-crank 65, which in turn operates the clutch member 62 into engagement with the member 60, thereby driving the chain 57 in the direc-

tion of the arrow shown in Fig. 2, it being understood that the member 62 of the clutch is driven through the medium of the gear 73 which is in mesh with the gear 74 on the shaft 28, the shaft 28 being driven through gears 75 and 76 from the motor 78. The wire is caught in the notched end of the mandrel 30, the mandrel being rotated by means of the shaft 28, and the wire is wound in spiral form on the mandrel, the free end of the wire being carried forward, on the mandrel 30 by the forming die 21 until all of the free end of the wire is wrapped in such shape upon the mandrel at which time the forming die strikes the arm 71 on the shaft 68 and the continued movement of the forming die moving the arm 71 operates the bell-crank 65 to disengage the clutch members 62 and 60, thereby stopping the movement of the chain 57. During the forward movement of the forming die above referred to, the follower 34 moves forward with the forming die, the mandrel with the spiral wire thereon extending through the openings 36 in the follower which affords a support for the same to prevent undue vibration of the mandrel. The forward movement of the follower by the spring 53 is limited by the rod 51 heretofore referred to, and upon the completion of the spiral by the forward movement of the die, the die is returned to its original position through the medium of the cable 41 pulled by the spring 49, the forming die pushing before it the follower 34 until the follower strikes the coiled springs 38 which act as a cushion, arresting the movement of the follower and forming die. After the spiral has been completed as above described the same is removed from the mandrel through the opening 36 in the follower and a new wire placed in the mandrel and the operation repeated.

I claim as my invention:

A stay machine comprising a base, a head-stock secured to said base, a tail-stock secured to said base, guide rods extending between and fixed to said head and tail stocks, a forming die slidable on said rods having a hole extending therethrough, a follower on said rods behind said die, said follower having an opening therethrough in alignment with the opening in said die, coiled cushion springs on said rods between said tail-stock and said follower, a rod slidably extending through said tail-stock fixed to said follower, a head on the outer end of said last-named rod, a coiled spring on said last-named rod between said follower and said tail-stock, a shaft mounted in said head-stock, a hollow mandrel secured to said shaft and having a notched outer end extending through the hole in said die, a stub shaft in said head-stock, means for driving said stub shaft from said first-named shaft,

clutch members on said stub shaft, a sprocket on one of said clutch members, a sprocket mounted in said tail-stock, a chain running over said sprockets, means for securing said 5 die to said chain to move said die positively forward, controlling means for said clutch operated by said die, and means for elasti-

cally returning said die after its forward movement.

In testimony whereof, I have hereunto set ¹⁰ my hand at Los Angeles, California, this 23rd day of January, 1917.

JOHN F. CALAHAN.
